United States Patent

Des. 241,548
Patented Sept. 21, 1976

241,548

AIR-CIRCULATING FIREPLACE

Lawrence M. Rheingold, Baldwin, and Alfred P. Rheingold, Freeport, N.Y., assignors to Templet Industries, Inc., Plainview, Long Island, N.Y.

Filed Sept. 23, 1975, Ser. No. 615,995

Term of patent 14 years

Int. Cl. D23—03
U.S. Cl. D23—97

FIG. 1

FIG. 2

FIG. 3

FIG. 4

FIG. 5

FIG. 1 is a top plan of an air-circulating fireplace showing our new design;

FIG. 2 is a front elevational view thereof;

FIG. 3 is a side elevational view taken from the right of FIG. 2;

FIG. 4 is a bottom plan view thereof; and

FIG. 5 is a rear elevational view thereof.

The cross hatched pattern which is shown in FIGS. 2-3 is understood to repeat across the entire area of the screen and to represent conventional screening.

We claim:

The ornamental design for an air-circulating fireplace, substantially as shown and described.
